UNITED STATES PATENT OFFICE.

ISAAC P. RICHARDS, OF PROVIDENCE, RHODE ISLAND.

DESIGN FOR A CENTERPIECE FOR TABLES.

No. 40,108.

Specification for Design.

Patented June 29, 1909.

Application filed April 30, 1909. Serial No. 493,231. Term of patent 14 years.

To all whom it may concern:

Be it known that I, ISAAC P. RICHARDS, a citizen of the United States, residing in the city and county of Providence, in the State of Rhode Island, have invented a new, original, and ornamental Design for a Center-piece for a Table, of which the following is a specification, reference being had to the accompanying drawings, forming part thereof.

Figure 1—is a perspective view of the ornamental center-piece. Fig. 2—is a side elevation of said center-piece.

The design of the center-piece consists essentially of a thickened disk-shaped base having an upright standard rising from the

center thereof and supporting a comparatively deep dish-shaped receptacle on its upper end. The middle portion of the standard is somewhat enlarged and has extending outward therefrom a large flat circular disk, having a circular binding or beading around its outer edge.

I claim:—

The ornamental design for a center-piece for a table, as shown and described.

ISAAC P. RICHARDS.
